Filed July 29, 1965, Ser. No. 475,788
1 Claim. (Cl. 340—276)

ABSTRACT OF THE DISCLOSURE

A burglar alarm system comprising detection elements at points of entry adapted to energize a triggering circuit, a housing remote from the detection elements containing energizing elements in connection with said triggering circuit to actuate an alarm circuit, said housing containing a selective circuit closing member manually reset with respect to the triggering circuit and movable axially to close the alarm circuit by the action of a solenoid energized in connection with the triggering circuit.

This invention relates to improvement in a burglar alarm system.

It is an object of this invention to provide a very simple alarm system having control means remote from and independent of the means used to energize and actuate the alarm means.

It is also an object of this invention to provide an alarm system embodying the use of portable control means which may be variously positioned.

More specifically, it is an object of this invention to provide a relatively small housing containing the triggering and energizing elements of the alarm system, said housing being arranged to be readily removably connected to a source of current.

It is also an object of the invention herein to provide low voltage alarm elements.

These and other objects and advantages of the invention will be set forth in the following description made in connection with the accompanying drawings in which like reference characters refer to similar parts throughout the several views and in which:

FIG. 1 is a view in perspective of the housing in connection with the invention herein;

FIG. 2 is a view in vertical section taken on line 2—2 of FIG. 1 as indicated;

FIG. 3 is a view similar to that of FIG. 2 showing a modification thereof with a detail thereof being shown in alternate position in dotted line;

FIG. 4 is a wiring diagram of the embodiment shown in FIG. 2 with some portions of the apparatus in broken view being shown in connection therewith;

FIG. 5 is a broken view in vertical section taken on line 5—5 of FIG. 4;

FIG. 6 is a broken view in vertical section taken on line 6—6 of FIG. 5 as indicated; and

FIG. 7 is a wiring diagram of the embodiment of FIG. 3 with some portions of the apparatus being shown in connection therewith.

With reference to FIGS. 1, 2 and 4—6, a preferred embodiment of the invention herein is shown.

A housing 10 is provided comprising a base plate 12 substantially rectangular in plan having a small depending

2

peripheral flange 13 and an upstanding cover 14 substantially parallelepiped in form having an open bottom to receive said base plate with said cover being adapted in a manner known in the art to frictionally engage said flange portion of said base plate.

Mounted as by screws onto said base plate is a solenoid 15 of known design here adapted to operate on a voltage such as of 24 volts and carrying a plunger 16 biased to extended position by the coil spring 17 carried thereon and bearing against a collar 18 on the adjacent side wall 15a of said solenoid. Said plunger has a reduced terminal portion 16a.

Upstanding from said base plate 12 in spaced facing relation and shown here as being of inverted T-shape in cross section are a pair of identical support and contact members 22 and 22'. Comprising said member 22 is its base portion 25 suitably secured as by screws to said base plate 12 and its upstanding wall portion 27, said wall portion being disposed in a plane at right angles to the plane of the adjacent side of said solenoid. Said wall portion has extending substantially centrally transversely therethrough an aperture 28 here indicated as being circular in cross section.

Carried on said wall and extending therethrough at either side of said aperture are electrical contacts 30 and 31 respectively comprising conductive bolts 30a and 31a threaded into plate-like conducting nuts 30b and 31b, as shown.

Said member 22' has portions corresponding to those of said member 22 indicated by like characters with a prime added. The respective apertures 28 and 28' are in axial alignment.

Carried between said support members 22 and 22' and having axial movement through said apertures 28 and 28' is a cylindrical rod 35 forming a drop switch member and is hereinafter referred to as a switch member. Said switch member 35 is of sufficient length to have its end portion 35a extend outwardly of the adjacent end wall 14a of said cover 14 through the aperture 14b therein.

Carried on said switch member 35 are electrical contacts shown as conductive coil springs 38 and 39. Pins 40 and 41 are disposed through said switch member 35 to retain said springs in a spaced relation. Said pins serve as stop members for the adjacent ends of said springs.

Said switch member is positioned to be engaged by the free end portion of the plunger 16 and is adapted to be retained in a given axial position by said plunger by means of a suitably positioned recess 35b therein here shown as an annular groove. Said recess 35b is so positioned axially of said switch member 35 that when said plunger is received within said recess, said coil spring 38 will bear against and connect said contacts 30 and 31. With said switch member 35 so positioned, said coil spring 39 will be free of engagement with said contacts 30' and 31'. When said plunger is withdrawn by said solenoid, said switch member will move axially to break contact with the contacts 30 and 31 and in the alternate engage the contacts 30' and 31'.

The alarm or signal means used may take on various forms. With reference to FIG. 4, a bell alarm 45 and a lighting means 48 are shown being used in connection with the embodiment of the invention here presented. Said bell alarm is shown provided with a switch 46a.

An actuating switch 43 is shown located in the jamb 44 of a door frame 45. Said switch is here shown com-

prising a spring biased button 43a which will engage the hinged edge of a door and will close the switch when the door is opened. A door 47 is indicated. Said switch includes electrical contacts 43b and 43c.

Circuits

With particular reference to FIGS. 3 and 4, a supply circuit 50 is provided comprising lines 51 and 52 respectively running to the contacts 20c and 20d of said transformer 20. Said supply circuit terminates in a connector in the form of a plug 56 which may be connected readily to a convenient receptacle in communication with a source or supply of current.

Running from said transformer 20 is an alarm triggering circuit 60 comprising lines 61 and 62. Said line 61 runs from contact 20b of said transformer to the contact 15b of said solenoid 15 and line 63 runs from the contact 15c of said solenoid to the contact 31a of said support member 22. A line 64 runs from the contact 30a of said support member 22 to the contact 43b of the switch 43, and running from the contact 43c thereof to the contact 20a of said transformer is said line 62. Said lines 62 and 64 are shown embodying the use of a separable connector 65. Completing the triggering circuit is the coil spring 38 carried on said switch member 35, which spring connects the contacts 30b and 31b which are integral with the contacts 30a and 31a respectively.

A third circuit of the invention herein comprises an alarm circuit 70. A line 71 runs from the contact 20d of the transformer 20 taking off from the line 52 to the contact 30'a of said support member 22'. A line 72 runs from the contact 31'a of said support member 22' to a separable connector 73 with a line 75 running from the other side of said connector to the contact 20c of said transformer and in circuit with said supply line 51.

The coil spring 39 when moved into operating position as will be described, will connect the contacts 30'b and 31'b to close the alarm circuit.

The alarm or signal means 46 and 48 are indicated as comprising a signal circuit 80 which includes the necessary wiring running to the connector 73 for removable connection with the alarm circuit 70. The details of such a circuit as circuit 80 are well understood and further description is not believed necessary.

It will be understood that where lines pass through the housing 10 that appropriate insulating grommets 85 will be used to protect said lines.

It is seen that the portions of the circuits contained within said housing 10 are provided with connectors for readily detachable connection with the detection switch and its immediate wiring and with said signal circuit 80 and with a source or supply of current.

Operation

The alarm system comprising the invention herein is arranged to be triggered or energized by the opening of a door or window as in a building or by the opening of a door as of a safe, of a vehicle or other type of enclosure.

The housing 10 contains the major elements operating the alarm system and is portable and adapted to be removably connected to a source of current, to a detection switch such as switch 43 located in a door jamb and to a signal means such as the audible alarm 46 and visual signal 48. Hence with the switch wired with an appropriate connector and the signal means wired with appropriate connectors, the arrangement may be adapted very readily for the housing to be plugged into the switch and signal circuits at various places.

The apparatus within the housing 10 is here shown connected to the switch 43, the signal circuit 80 and to a source of current. With the detection switch 43 closed by the opening of a door, the triggering circuit 60 will be closed energizing the solenoid 15 to retract

the plunger 16 from its normally extended position. With the plunger 16 retracted, the member 35 will be urged by the spring 38 or it may fall by gravity in the direction of the member 22' for engagement between the spring 39 and the contacts 30'b and 31'b. The member 35 bearing against the coil spring 39 will provide good contact between said spring and said contacts. With the alarm circuit 70 thus being closed, the signal circuit 80 will become energized actuating the signal means.

It is seen that the alarm circuit is independent of the triggering circuit once it has become energized and the signal means will operate until the member 35 is manually reset to its inoperative position relative to the alarm circuit with the coil spring 38 in engagement with the contacts 30b and 31b. It is retained in this position by the plunger 16. It will be understood that while retained in this non-operative position, the switch 43 must be in inoperative or in open position either by use of a switch such as a toggle switch or the entrance or door must be closed. During non-use hours, if desired, the plug 56 may be disconnected from the current supply source. In FIG. 4, the member 35 is shown in inoperative position relative to the alarm circuit 70, and in FIG. 2 said member is shown in operative position closing 25 said alarm circuit.

Modification

With reference to FIGS. 3 and 7, a modification of the invention herein is shown in which portions identical with those of the previous embodiment described will bear like numerals for identification and will not be further described. The new or modified portions present in this embodiment are hereinafter described.

The changes in the modified structure consist of the use of a second transformer 95 in parallel with said transformer 20 by means of the lines 91 and 92 and is provided to reduce the voltage through the alarm circuit to 24 volts as here indicated. A line 93 runs from said transformer 95 to the contact 30'a. The line 72 runs from the contact 31'a to the alarm means indicated by the numeral 98 and said means are adapted to operate with said reduced voltage. The line 96 provides the return from the alarm means to said transformer 95.

In all other respects the modified structure operates in the same manner as the embodiment first above described.

Thus it is seen that we have provided an efficient simply constructed and simply installed burglar alarm system for operation with both full line voltage and reduced voltage and wherein the alarm system once actuated is independent of the alarm triggering or actuating means.

It will of course be understood that various changes may be made in the form, details, arrangement and proportions of the parts, without departing from the scope of applicants' invention which, generally stated, consists in a device capable of carrying out the objects above set forth, in the parts and combinations of parts disclosed and defined in the appended claim.

What is claimed is:

1. An alarm system of the type indicated having in combination,
- 60 detection means,
- electrically operated signal means,
- a normally open triggering circuit including said detection means,
- a normally open alarm circuit including said signal means,
- a housing,
- a solenoid in said housing included in said triggering circuit, a plunger carried by said solenoid spring biased to extended position,
- a pair of conductive upstanding support members spaced apart adjacent said solenoid, said support members having a pair of aligned apertures, one of said support members being included in said triggering circuit, the other of said support members being included in said alarm circuit,

a circuit closing member carried by said support members movable axially therebetween, said circuit closing member comprising a rod slidably disposed through said apertures,
 a pair of spaced electrical contacts carried by said rod, 5
 said rod having a recess therein to receive the extended end portion of said plunger, said recess being positioned on said rod that when engaged by said plunger, said first one of said contacts is in circuit with said triggering circuit, and
 said rod being axially self movable for engagement of
 said other contact to be in circuit with said alarm
 circuit when said plunger is withdrawn from said recess.
